UNITED STATES PATENT OFFICE.

WILBUR D. MEASE, OF McMECHEN, WEST VIRGINIA.

LOCOMOTIVE DRIVING-BOX WEDGE ADJUSTER.

Application filed January 16, 1924. Serial No. 636,610.

To all whom it may concern:

Be it known that I, WILBUR D. MEASE, a citizen of the United States, residing at McMechen, in the county of Marshall and State 5 of West Virginia, have invented new and useful Improvements in Locomotive Driving-Box Wedge Adjusters, of which the following is a specification.

This invention relates to wedge adjusters 10 for the wedges of locomotive driving boxes, the general object of the invention being to so form the adjusters that they can be easily replaced when damaged, without removing the pedestal cap.

15 Another object of the invention is to so form the parts that the wedge can have limited movement to prevent damage to the adjuster.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying 30 drawings wherein like characters denote like or corresponding parts throughout the several views, and in which:—

Figure 1 is an elevation showing the invention in use.

Figure 2 is a section on line 2—2 of Figure 1.

35 Figure 3 is a section on line 3—3 of Figure 2.

Figure 4 is a section on line 4—4 of Figure 2.

Figure 5 is a perspective view of the lower 40 portion of a wedge.

In these views 1 indicates a frame, 2 the pedestal cap and 3 the wedge. As is well known a bolt is used for adjusting the wedge, said bolt passing through the 45 pedestal cap with its end projecting so that this end can be engaged by a wrench in order to adjust the wedge. These bolts are frequently damaged by coming in contact with various objects so that they have to be renewed. This is a difficult job as it requires 50 the removal of the pedestal cap.

It is the object of my invention to so form the adjusters that they can be removed and replaced without removing the pedestal cap.

55 In carrying out my invention I provide a

bolt 4 and a head 5 which is detachably connected with the bolt so that either part can be removed without removing the pedestal cap. The head 5 engages the slot 6 formed in the lower end of the wedge 3 and has its 60 enlarged upper end provided with the beveled faces 7 which are so formed as to permit play of the wedge and thus prevent damage to the head if the wedge should be moved laterally. This end of the head is 65 also provided with a hole 8 for receiving a pin or tool to hold the head against turning movement when the bolt is being placed in engagement therewith or is being disengaged therefrom. The lower end of the 70 head is provided with a screw threaded socket 9 for receiving the upper end of the bolt and these parts are fastened together by a pin 10. The upper end of the socket 75 9 is of cone shape to receive the cone-shaped end of the bolt, this formation of the parts and the pin 10 acting to remove strain from the threads of the screw and socket. The pedestal cap is provided with slots 11 for receiving the lower ends of the heads and 80 when it is necessary to remove an adjuster the adjuster is turned until the pin 10 is in alignment with the slot 11 so that it can be knocked out to permit the screw to be unscrewed from the head. A pin is placed in 85 the socket 8 through the slot 6 in the wedge to hold the head against turning movement when the screw is being removed therefrom or inserted in the head.

From the foregoing it will be seen that 90 I have provided means whereby the adjusters can be easily and quickly removed and replaced without removing the pedestal cap. The beveled faces on the enlarged part of the head permits a certain amount of 95 play of the wedge which prevents damage to the head and the pin 10 and the cone-shaped upper end of the screw acts to remove strain from the threads of the screw. Either the screw or its head can be removed 100 and replaced by a new one so that if one is damaged this damaged part need only be replaced as the undamaged part can be used with the new part.

It is thought from the foregoing description that the advantages and novel features of my invention will be readily apparent.

I desire it to be understood that I may make changes in the construction and in the combination and arrangement of the 110

several parts, provided that such changes fall within the scope of the appended claims.

What I claim is:—

- 5 1. A wedge adjuster of the class described comprising a head for engaging a wedge, a screw detachably engaging the head, said head having beveled faces on the part which engages the wedge for permitting play of the wedge.
- 10 2. A wedge adjuster of the class described comprising a head, having a threaded socket, a screw engaging said socket and a pin passing through the socket and screw for holding the parts together.
- 15 3. A wedge adjuster of the class described comprising a head having a threaded socket, a screw engaging said socket, a pin passing

through the socket and screw for holding the parts together, the upper end of the screw being of cone shape to engage the cone-shaped upper end of the socket.

- 20 4. A wedge adjuster of the class described comprising a head having an enlarged upper end provided with beveled faces for permitting play of the wedge, said enlarged upper end having a hole therein, the lower end of the head having a threaded socket, a screw having its upper end engaging the threaded socket, a pin for connecting the screw with the head, the upper end of the screw being of cone shape to engage the cone-shaped upper end of the socket.

In testimony whereof I affix my signature.

WILBUR D. MEASE.
